FRAME

Jacob Schoenfeld, New York, N. Y.

Application January 3, 1931. Serial No. 506,359

3 Claims. (Cl. 150—29)

This invention relates to frames, and more particularly to bag frames such as hand-bags or pocket books and purses.

The objects of the invention are to provide a bag frame with inverted channels having improved locking means therefor; to utilize the depth of the channel for one of the locking members; to thereby obtain a locking means which will exert resilient pressure for holding the frames tight when closed; to overcome the necessity of welding the resilient locking member to the frame; to avoid interference of the locking member with applying the leather or other covering on the frame; to provide a locking member which can be riveted to the frame without distorting the frame by the riveting operation; to avoid attachment of the locking member to the inner wall of the frame member where the rivets would show or add objectionable thickness; to secure simplicity of construction and operation; and to obtain other advantages and results as may be brought out in the following description.

Referring to the accompanying drawing in which like numerals of reference indicate similar parts throughout the several views:

Figure 1 is an elevation, with part of one outer wall broken away, of a frame embodying my invention;

Figure 2 is a sectional plan on line 2—2 of Fig. 1;

Figure 3 is a sectional view on line 3—3 of Fig. 1;

Figure 4 is a detail elevation of the hinge portion of one of the locking members, the locking portion thereof being shown in dotted lines; and

Figure 5 is an extended view of the blank from which said hinge portion is formed.

In the specific embodiment of the invention illustrated in said drawing, the reference numerals 1, 2 indicate two frame sections hinged together as at 3, 3, and adapted to swing flatwise together as is usual in the construction and use of frames for hand-bags and the like. Said frame sections are each of channel formation, with one wall of the channel of one section adapted to close against one wall of the other section, and for convenience, these particular walls of the two sections will be referred to as the inner walls 4, 5 of sections 1, 2 respectively. The two walls of the channel members which are farthest apart when the frame is closed, will be referred to as the outside walls 6, 7 of the sections 1, 2 respectively. The walls of each channel member or section which join the inner and outer walls,

will be referred to as the bottom walls 8, 9 of sections 1, 2 respectively. The channels are preferably outwardly open, that is, the bottom wall is at the inside edge of the side walls rather than at the outside edge thereof as has been most customary for years past. The present type of frame with the channels outwardly open are popularly known as "inverted frames", and in use of the same, the leather or other material forming the pouch or body of the bag covers the outside wall and is turned over the upper or outer edge thereof so as to be introduced into the channel. Therefore, when the bag is closed, only the thin outer edge of the inner wall is visible.

An important feature of the present invention resides in the provision of a novel locking member for securing the frame sections together in tightly closed condition. The locking member referred to provides a hinge portion 10 and a locking portion 11, these parts being held assembled by an elongated or wire spring 12. Said hinge portion 10 as shown provides a plurality of curled ears 13 in alignment with each other and arranged longitudinally of the channel of the frame section, the ears being here shown as substantially at the open side of the channel. The locking member has a plurality of similar ears 14 in alignment with each other and adapted to be aligned with the ears of the hinge member, between the same. The spring 12 extends through the aligned ears, and accordingly both holds the members assembled and acts as a hinge-pin. Preferably the spring 12 provides a flattened portion extending within the ears, and the formation of the ears on the locking member is such that the said ears cannot rotate with respect to the spring as a result of which swinging the locking member obtains a twisting of the spring. This twisting of the spring is made effective by providing an appropriate off-set in a part of the spring away from the ears of the locking member. As here shown, the further end of the spring is angularly disposed and adapted to engage a sufficient part of the side wall of the channel to hold that end of the spring substantially stationary. If desired, an initial tension may be given the spring so that it will hold the locking member in a depressed position.

The locking member is preferably transverse to the hinge member so that the hinge member extends from the line of hinging down into the channel, and the locking member lies across the channel, overlying the other frame section also. A projecting detent 11' in this other channel may

be releasably engaged by the locking member for holding the frames closed.

A further feature of the present invention, is to provide a construction wherein the hinge section 5 of the locking member may be carried by and be attached to the bottom wall of the channel frame. Such attachment has several advantages, amongst which are the greater ease of assembly in being able to rivet the attaching 10 means and head the rivets against a solid supporting of the end wall as distinguished from the resilient or movable nature of the side wall of the channel when trying to rivet a part thereto. Further advantages reside in the fact that the 15 hinge portion may be positioned entirely within the frame channel, the pouch material may be turned over the entire length of the channel without having to make a cut-out for the locking member. So it is, in carrying out the feature of 20 the invention under discussion, the hinge portion 10 is provided preferably of the construction shown. Said hinge portion may be constructed from a blank of sheet material symmetrically shaped with respect to a center line, such that 25 the blank may be doubled substantially on that center-line and provide a device of double thickness or two plies, but of substantially half the width of the original blank. In doubling the blank, the doubled edge is not squeezed tightly 30 together, but is left rounded so as to provide an open longitudinal passageway for the spring 12 heretofore described. Furthermore, the blank, as shown in extended condition in Figure 5, is provided with symmetrically disposed cut-outs 35 which extend across the said center-line of the blank such that the metal between the cut-outs and between the cut-outs and the ends of the blank will form the curled ears 13 of the completed device. As shown, the major portions of 40 the doubled blank are brought flatwise together and extend in that condition to the edge of the device opposite to the curled edge. The distance from one said edge to the other is preferably less than the depth of the channel, so that the device 45 is entirely within the channel in use. The formation of the ears 13 is such as to permit the spring to turn therein.

At the edge of the hinge section 10 opposite from the curled edge or edge having the ears 50 13, are provided means for attaching the section to the channel section. The means here shown comprises integral shanks or rivets 17 projecting from the said edge. In the formation of the blank, similarly shaped and oppositely disposed projections are provided so that when the 55 blank is doubled these projections will lie flatwise together and thereby constitute a double rivet 17 in the completed construction. As many of these rivets 17 may be formed as found necessary or desirable, the present disclosure providing one adjacent each end of the hinge section. Appropriate perforations are provided in the bottom wall of the frame section, properly proportioned and spaced to receive the rivets 60 17 projecting from the hinge section. After the rivets are inserted in the perforations, said rivets are upset or headed so as to securely and permanently assemble the said hinge section in the channel. Due both to the double thickness of the material forming the hinge section and to the practicability from a mechanical standpoint of tightly riveting the same in place without distortion of the channel, the hinge section will 65 70

stand parallel to the side walls of the channel and not require the side walls either for support or attachment. Consequently the hinge section may be and preferably is spaced from one or both of the said side walls, and particularly from the outer side wall for the purpose of enabling the pouch material to be introduced between said outer side wall and the hinge section. If desired, this spacing may be assured by provision of one or more bosses or center-punches 15 on the face 80 of the hinge section which is to be spaced from the side wall. In the present showing I have shown several of these bosses projecting from only one face of the hinge section, but may use any number at such places as found desirable. 85 90

It is a further feature of the present invention to resiliently draw the two inner walls of the channel members closely together in closed and locked condition. This feature is accomplished by the construction and arrangement of parts 95 shown and described, in that the locking member has a hinge portion of a material depth, secured at its lower edge thereby affording a resiliently movable upper edge for said portion. The parts may be so proportioned that when the lock- 100 ing member engages the catch, the hinge section of said locking member is tilted from normal position, this distortion exerting a tension upon the latch which draws the frame sections together. 105

Obviously detail changes and modifications may be made in the construction and use of my improved frame, without departing from the spirit or scope of the invention, and I do not wish to be understood as limiting myself to the 110 exact construction shown or described, except as set forth in the following claims when construed in the light of the prior art.

Having thus described the invention, I claim:—

1. A frame as characterized, comprising a 115 channel section, a locking member carried by said section and located in part between the channel walls of said section so as to project from the open side of said channel, and means above the bottom wall of the channel for retaining the locking member spaced from one of the side walls for enabling the handbag fabric to be applied therebetween.

2. A frame as characterized, comprising a 125 channel section, a locking member carried by said section and located in part between the channel walls of said section so as to project from the open side of said channel, and a boss on one side face of said member at a part thereof within the channel for engaging one of the side walls of the channel and retain the member spaced therefrom for enabling the handbag fabric to be applied between said wall and member.

3. A frame as characterized, comprising a pair of channel sections adapted to be closed together 135 with inner walls of the channels contiguous, a locking member carried by one of said sections so as to project from the open side of the channel and with a portion within the channel, and a boss on the side face of said member away from the other frame section for engaging the wall of the channel remote from said other section and retain the member spaced from said wall for enabling the handbag fabric to be applied between said wall and member at the outside of 140 145 the frame section.

JACOB SCHOENFELD.
